ELECTRIC HAND LAMP

Josef Krös, Frankfert-on-the-Main, Germany

Application March 31, 1934, Serial No. 718,507
In Germany July 16, 1932

8 Claims. (Cl. 240—52.1)

My invention relates to an electric hand lamp which can be attached to any article by means of a spring clamp. The part which carries the lamp bulb is rotatably mounted on the spring clamp, whereby the rays of the lamp can be directed towards any point independently of the position of the clamp. The spring clamp is so formed that it acts by pressure and friction on the article on which it is clamped in order to effect a secure hold on articles of any shape. The bulb socket is in one piece with the ring which surrounds the spring clamp and may be of insulating material, and spring rods are provided which partially form the pivot of the clamp and partially lie at right angles thereto and constitute the braking fixation of the ring, whereby the bulb is automatically secure in every position relative to the clamp. A self-locking device may also be provided for the bulb provided with a reflector.

20 The utility of the hand lamp extends to all places having an electric supply, such as works, mills, industrial establishments and so forth.

In the accompanying drawing which illustrates a constructional example,

25 Figure 1 is a side elevation,
Figure 2 is a rear elevation.

Figures 3 and 3a are detached front and fragmentary side elevations respectively of parts of the clamp.

30 Fig. 4 is a view in section taken on line A—B of Figure 1.

Figure 5 is a view in section taken on line C—D of Figure 4 and

35 Figure 6 is a view in section taken on line E—F of Figure 4.

In the drawing, the lamp casing *a* has a tubular lug *b* and is mounted on the socket *c* which is of insulating material and has a ring *d* provided with tooth shaped indentations. A resilient, 40 semiannular ring *e* is connected by a pin *f* to the neck of the socket *c* and engages with nose-like projections *g* in the tooth-like indentations of the ring *d*, whereby the rotatable lamp casing is locked in every position. The bulb *h* is mounted 45 in a corresponding screw thread in the socket *c* and receives current through the contact pins *i* and *k* in the usual manner.

The current is supplied through a cable *l* which engages by means of a bend *m* with a recess *n* 50 in the socket *c*, the recess communicating with two passages *o* and *p* which lead the electric wires to the contact pins *i* and *k*. The arrangement of the cable in the above described manner secures the connections against breakage by a pull on 55 the cable.

The socket *c* has a ring-shaped extension *q* the inner part of which is turnably engaged by crosswise arranged rods *r* and *s* which are mounted in sleeves *t* and *u* and are acted on by compression springs. The sleeve *t* forms the pivot for 5 the clamp jaws *v* and *w* which are kept in the clamping position by means of a spring *x*. The jaws each carry at the clamping point a pair of semi-cylindrical presses *y* of rubber, which are tiltably mounted by the aid of wires *z* in the jaws 10 *v* and *w* respectively. The tilttable mounting of the presses permits them to accommodate themselves to the shape of the article to which the lamp is clamped, and owing to the twin semi-cylindrical form of the presses an attachment to 15 the said article takes place by pressure and friction. Owing to the tiltability at the clamping point each pull strengthens the grip on the said article. The presses are preferably formed of rubber having cotton or other fibrous material 20 extending through it. The tilting effect and strengthening of the attachment is improved if each semi-cylindrical part *y* has a separate turning place *z* or *z'*. The clamp jaw *v* engages the rod *s* by means of a circular hole and only the 25 jaw *w* is rendered movable relative thereto by means of a slot *z''* whereby the application of the hand lamp to a supporting article is facilitated.

The whole bulb socket can be turned 360 degrees round the clamp and remains fixed in every position, and the lamp casing *a* can also be turned 360 degrees and also remains fixed in every position.

I claim:

1. In a portable electric lamp, the combination 35 with a lamp socket provided with an annular extension the center axis of which extends at a right angle to the longitudinal axis of said socket, of a clamp extending through the opening of said annular extension, said clamp comprising two jaws pivotally mounted between their ends on means forming a pivot axis which is positioned diametrically in the opening of said annular extension and slidably abuts with both of its ends 40 45 the inner side thereof, whereby said lamp socket may be adjusted to any position in a circle about the longitudinal axis of said clamp.

2. In a portable electric lamp, the combination 50 with a lamp socket provided with an annular extension the center axis of which extends at a right angle to the longitudinal axis of said socket, of a clamp extending through the opening of said annular extension, said clamp comprising two jaws pivotally mounted between their ends on a 55

5 pivot axis which is positioned diametrically in the opening of said annular extension and slidably abuts with both of its ends the inner side thereof, whereby said lamp socket may be adjusted to any 10 position in a circle about the longitudinal axis of said clamp, and means fixedly secured to said pivot axis and slidably engaging the annular extension of said lamp socket for preventing tilting movement of the latter about the pivot axis of 15 said clamping jaws.

10 3. In a portable electric lamp, the combination with a lamp socket provided with an annular extension the center axis of which extends at a right angle to the longitudinal axis of said socket, 15 of a clamp extending through the opening of said annular extension, said clamp comprising two jaws pivotally mounted between their ends on a common pivot axis which is positioned diametrically in the opening of said annular extension 20 and slidably abuts with both of its ends the inner side thereof, whereby said lamp socket may be adjusted to any position in a circle about the longitudinal axis of said clamp, said pivot axis comprising a tube, rods slidably arranged in the 25 ends of said tube and projecting therefrom and means for urging the rods outwardly in engagement with the inner side of said annular extension.

4. In a portable electric lamp, the combination 30 with a lamp socket provided with an annular extension the center axis of which extends at a right angle to the longitudinal axis of said socket, of a clamp extending through the opening of said annular extension, said clamp comprising two 35 jaws pivotally mounted between their ends on a common pivot axis which is positioned diametrically in the opening of said annular extension and slidably abuts with both of its ends the inner side thereof, whereby said lamp socket may be 40 adjusted to any position in a circle about the longitudinal axis of said clamp, and a lamp casing adjustably secured to the lamp socket and adapted to be rotatably adjusted about the axis of the same.

45 5. In a portable electric lamp, the combination with a lamp socket provided with an annular extension the center axis of which extends at a right angle to the longitudinal axis of said socket, of a clamp extending through the opening of said annular extension, said clamp comprising two 50 jaws pivotally mounted between their ends on means forming a pivot axis which is positioned diametrically in the opening of said annular extension and slidably abuts with both of its ends the inner side thereof, whereby said lamp socket 55 may be adjusted to any position in a circle about the longitudinal axis of said clamp, and a lamp casing adjustably secured to the lamp socket and adapted to be rotatably adjusted about the axis of the same, said lamp casing having a light 60 emitting opening arranged in a plane parallel to the axis of said socket.

6. In a portable electric lamp, the combination 65 with a lamp socket provided with an annular extension the center axis of which extends at a right

angle to the longitudinal axis of said socket, of a clamp extending through the opening of said annular extension, said clamp comprising two jaws pivotally mounted between their ends on a common pivot axis which is positioned diametrically in the opening of said annular extension and slidably abuts with both of its ends the inner side thereof, whereby said lamp socket may be adjusted to any position in a circle about the longitudinal axis of said clamp, and means secured to said axis and engaging the annular extension of said lamp socket for preventing tilting movement of the latter about the pivot axis of said clamping jaws, said means comprising tubular members fixedly secured at a right angle to 15 said pivot axis, rod-like members slidably arranged in the outer ends of said tubular members and projecting therefrom and means for urging said rod-like members outwardly in engagement with the inner side of the annular extension 20 of said socket.

7. In a portable electric lamp, the combination with a lamp socket provided with an annular extension the center axis of which extends at a right angle to the longitudinal axis of said socket, of a 25 clamp extending through the opening of said annular extension, said clamp comprising two jaws pivotally mounted between their ends on a common pivot axis which is positioned diametrically in the opening of said annular extension 30 and slidably abuts with both of its ends the inner side thereof, whereby said lamp socket may be adjusted to any position in a circle about the longitudinal axis of said clamp, and a spring about said pivot axis and engaging one end of each jaw 35 for urging the other ends of the jaws into closed position, and a pair of rubber presses mounted pivotally in double bearing on each clamping end of the jaws, said presses being provided with substantially semi-cylindrical pressure faces. 40

8. In a portable electric lamp, the combination with a lamp socket provided with an annular extension the center axis of which extends at a right angle to the longitudinal axis of said socket, of a clamp extending through the opening of said 45 annular extension, said clamp comprising two jaws pivotally mounted between their ends on a common pivot axis which is positioned diametrically in the opening of said annular extension and slidably abuts with both of its ends the inner side thereof, whereby said lamp socket may be 50 adjusted to any position in a circle about the longitudinal axis of said clamp, and means including spring pressed rod members secured to said axis and engaging the annular extension of said lamp 55 socket for preventing tilting movement of the latter about the pivot axis of said clamping jaws, one of said clamping jaws being provided with a circular hole through which one of said rod members passes to prevent its movement, the other jaw being provided with a slot through which the other rod member passes to prevent its movement. 60
